LOCKING CENTER PIN FOR BODY AND TRUCK BOLSTERS OF RAILWAY CARS

Stacy B. Haseltine, La Grange, Ill., assignor to
W. H. Miner, Inc., Chicago, Ill., a corporation
of Delaware

Application October 8, 1947, Serial No. 778,623

10 Claims. (Cl. 105—200)

1

This invention relates to improvements in locking center pins for connecting the body and truck bolsters of railway cars.

One object of the invention is to provide a locking center pin for the body and truck bolsters of a railway car provided with pin receiving openings and annular shoulders surrounding said openings respectively, comprising a plurality of outer members having shouldered engagement at opposite ends with the shoulders of the bolsters, and a filler element for holding the outer members of the pin spread apart in said shouldered engagement, wherein simple and efficient means is provided for holding the filler element against removal from between the outer members.

A more specific object of the invention is to provide a center pin as set forth in the preceding paragraph, wherein the locking means is in the form of a plug supported on shoulders on the outer members, and on which the filler element rests, the plug being displaceable to out of the way position with respect to the filler element to permit removal of the latter from between the outer members.

Other objects of the invention will more clearly appear from the description and claims herein-after following.

In the accompanying drawings forming a part of this specification, Figure 1 is a vertical sectional view through the body and truck bolsters of a railway car, illustrating my improved center pin in connection therewith. Figure 2 is a bottom plan view, on an enlarged scale, of the center pin shown in Figure 1. Figure 3 is a horizontal sectional view, on an enlarged scale, corresponding substantially to the line 3—3 of Figure 1. Figure 4 is a horizontal sectional view, corresponding substantially to the line 4—4 of Figure 6. Figures 5 and 6 are vertical sectional views, corresponding substantially to the line 6—6 of Figure 2, Figure 5 showing the locking plug, which is in the form of a ball, displaced to permit removal of the filler element of the pin, and Figure 6 showing the locking plug in the locking position. Figure 7 is a top plan view, on an enlarged scale, of the pin shown in Figure 1. Figure 8 is a detailed perspective view of one of the outer members of my improved center pin. Figure 9 is a detailed perspective view of the filler of the center pin. Figure 10 is a broken side elevational view of my improved center pin, illustrating another embodiment of the invention. Figure 11 is a bottom plan view of Figure 10. Figure 12 is a transverse vertical sectional

2

view, corresponding substantially to the line 12—12 of Figure 11. Figure 13 is a transverse vertical sectional view of one of the outer members of the pin, showing the locking plug, which is in the form of a wedge-shaped block, in the laterally displaced position which permits removal of the filler element.

In said drawings, referring first to the embodiment of the invention illustrated in Figures 1 to 9 inclusive, 10 indicates the body bolster of a railway car, and 11 the truck bolster. The body and truck bolsters 10 and 11 are of well-known design, the body bolster including the usual center section 12 adapted to receive the center pin. The section 12 is of cylindrical tubular form and protrudes beyond the bottom of the body bolster. The upper end of the section 12 presents an annular shoulder or seat on which the head at the upper end of the center pin is adapted to rest. The truck bolster 11 has the usual downwardly opening pocket 13 adapted to accommodate the head at the lower end of the center pin, and is provided with a pin receiving opening 14 communicating with said pocket and in vertical alignment with the pin receiving opening provided by the center section 12 of the body bolster. The wall surrounding the opening 14 provides a downwardly facing shoulder with which the head at the lower end of the center pin is engageable to limit upward displacement of the pin with respect to the truck bolster. The bolsters 10 and 11 have the usual bearing plates 15 and 16 interposed therebetween.

My improved center pin, as illustrated in Figures 1 to 9 inclusive, comprises broadly three outer members A—A—A, a filler element B, and a plug C in the form of a ball.

The outer members A, which are three in number, are arranged symmetrically about the central vertical axis of the pin. Each member A is of sector-shaped cross section, having laterally diverging, inner faces 17—17, and a curved outer face 18. At the top and bottom ends, each member A is provided with relatively heavy, laterally outwardly projecting, horizontal flanges 19 and 20, which form top and bottom head portions. The three members A—A—A of the pin are identical and, when assembled, define a sectional, cylindrical pin having a shank of circular cross section and heads at opposite ends. The top flange 19 of each outer member is eccentric to the cylindrical outer face 18 of said member, as shown in Figure 7, being of such a size that it will readily pass through the pin receiving openings of the truck and body bolsters

when the filler element B is absent and the sections of the pin formed by the members A—A—A are in contracted condition. The bottom flanges 20—20—20 of the three outer members are concentric with the cylindrical shank of the pin and form head members which are adapted to overlap the shoulders surrounding the opening 14 of the truck bolster.

The bottom flange or head 20 of each outer member A is provided with an opening or guideway 21 therethrough, the same being inclined downwardly in inward direction. The bottom wall of the guideway 21 at the inner end portion of the latter is recessed to provide a concave seat portion 22 for the corresponding side of the ball-shaped plug C. At the outer end portion of the guideway 21, the bottom wall is slotted, as indicated at 23, to render the ball-shaped plug accessible for manipulation and removal.

From the foregoing, it will be evident that the seats 22—22—22 of the heads at the lower ends of the outer members A—A—A present three circumferentially spaced supports for the ball-like plug, which supports are spaced outwardly away from the central vertical axis of the pin, thereby providing an opening between the same, giving access to the ball-shaped plug for manipulation.

The filler element B comprises three platelike wings 24—24—24, radial to the central longitudinal axis of the pin. The wings 24—24—24 are spaced equal distances apart and merge at the center of the pin to form a central shank portion 25. The platelike wings of the filler element are of such a thickness as to fill the spaces between the outer members to form, with said outer members, a complete pin of true cylindrical form. At the lower end portion thereof, each wing is laterally enlarged to provide a projecting lug-like portion 26 forming a head adapted to limit upward displacement of the filler element by shouldered engagement with the shoulder at the opening 14 of the truck bolster. The lugs 26—26—26 of the filler element are of lesser thickness than the bottom flanges of the outer members of the pin, whereby the filler element may be forced upwardly to a sufficient extent with respect to the outer members so that the locking plug may be moved to unlocked position. Below the lugs 26—26—26, the element B is provided with a central pocket 27 with which the guideways 21—21—21 of the members A communicate. The pocket 27 is elongated vertically and has the top wall thereof cut out to present a downwardly facing, concave seat 28, adapted to engage over the top of the ball-shaped plug C.

In the assembled and applied condition of the pin, the ball C is supported on the seats 22—22—22 of the outer members of the pin and the filler element B rests on the ball, the upper portion of the latter being engaged in the seat 28. As will be evident, the filler element of the pin is thus effectively held against removal in downward direction from between the outer members.

In applying the center pin illustrated in Figures 1 to 9 inclusive to the bolsters, the three outer members A—A—A are assembled with the bolsters by first inserting two of the same in the pin receiving openings and spreading the same apart to bring the heads thereof in shouldered engagement with the bolsters, and then insert-

ing the third outer member between the two members first applied and displacing said third outer member radially outwardly to bring the heads thereof into shouldered engagement with the bolsters, the ball C having been placed within the guideway 21 of said third outer member before the latter is inserted in the bolster openings. During application of this third member, while the same is being inserted between the other two members, the ball C is manually held in the guideway 21 to clear the inner sides of the lower end portions of said two members, being retained in approximately the position shown in Figure 5 until it has passed the seat portions of said members, whereupon it will roll to the position shown in Figure 6 and rest on the three seats 22—22—22 of the members A—A—A. After the outer members have been thus positioned within the bolster openings, the filler element B is applied by inserting the same in upward direction between the outer members A—A—A, engaging the wings 24—24—24 thereof in the spaces between said outer members. As the filler element is pushed upwardly, it crowds the ball C to one side into the guideway 21 of one of the members A, being displaced to approximately the position shown in Figure 5. The filler element is pushed upwardly or lifted a sufficient distance to permit the ball C to roll or drop into the pocket 27 and seat on the seats 22—22—22 of the outer members. After the ball has been thus seated, the filler element is dropped to engage the top of the ball, as shown in Figure 6. The ball C in its interposed position between the seats 22—22—22 of the outer members and the bottom portion of the filler element effectively blocks removal of the filler element in downward direction.

To remove the pin from the bolsters, substantially the reverse procedure is followed, the filler element B being first pushed upwardly from the position shown in Figure 6 to that shown in Figure 5, thus unseating the ball C and registering the openings of the pocket 27 with the openings of the guideways 21—21—21. The ball C is then pushed laterally into the guideway of any one of said outer members to clear the follower element, whereupon the latter may be removed to permit collapse and removal of the outer members A—A—A of the pin.

Referring next to the embodiment of the invention illustrated in Figures 10, 11, 12 and 13, the construction is similar to that hereinbefore described, with the exception that the plug, which is indicated by D, is in the form of a wedge and the guide openings of the outer members are modified to cooperate therewith.

The pin illustrated in these figures includes three outer members E—E—E, identical with the outer members A—A—A, with the exception that the guideways 121 for the wedge plug D are shaped to guide the plug, which is in the form of a six-sided wedge, and that the lower end portions of the lower heads of the pin, which heads are indicated by 120—120—120, are preferably grooved, as indicated by 129, to receive a U-shaped spring clip 130, to yieldingly hold the outer members E—E—E in place and serve as an additional safety device similar to a cotter pin, the clip being engaged about two of the outer members E—E and having its arms 133, which are curved outwardly at their ends, engaged through and seated in an opening 134 in the filler element F. The filler element F of this pin is similar to

the filler element B hereinbefore described with the exception that the pocket 127 thereof, which receives the plug D, is shaped to accommodate this particular plug. The top wall of the pocket 127 is substantially flat, as indicated at 131, to seat squarely on the flat top surface 132 of the plug. The plug D is applied and removed in substantially the same manner as the plug C and supports the filler element F against downward displacement by having its wedge faces seated on the inner ends of the bottom walls of the guideways 121—121—121.

I claim:

1. In car construction, the combination with body and truck bolsters having aligned center pin receiving openings; of a center pin insertable from beneath said truck bolster, said pin including a plurality of outer members headed at opposite ends; a filler element interposed between said outer members, said filler element holding the heads of the outer members in shouldered engagement with the bolsters; supporting shoulders on said outer members; and a locking plug supported on said shoulders, said plug supporting the filler element, said outer members being recessed above said shoulders to accommodate said plug for lateral displacement clear of said filler element, said plug, when lifted off of said shoulders, being laterally displaceable into one of said outer members to permit removal of said filler element in a downward direction.

2. In car construction, the combination with body and truck bolsters having aligned center pin receiving openings; of a center pin insertable from beneath the truck bolster, said pin including a plurality of outer members headed at opposite ends; a filler element interposed between said outer members, said filler element holding the heads of the outer members in shouldered engagement with the bolsters, said outer members having radial guide openings therein, and depressed supporting shoulders at the inner ends of said openings; and a locking plug supporting said filler element against downward displacement, said plug being supported on said shoulders of the guideways, said plug, when lifted above said shoulders, being laterally displaceable into the guideway of one of said outer members clear of said filler element to permit withdrawal of the latter in a downward direction from between the outer members.

3. In car construction, the combination with body and truck bolsters having aligned center pin receiving openings; of a center pin insertable from beneath said truck bolster, said pin including a plurality of outer members headed at the top and bottom ends, a radial guideway in the lower head of each outer member, said guideway being inclined downwardly in inward direction and open at its inner end; a depressed seat at the inner end of each guideway; a filler element interposed between said outer members, said filler element holding the heads of the outer members in shouldered engagement with the bolsters, said filler element having a portion thereof depending between the seats of the outer members, said depending portion having a pocket communicating with the inner ends of the guideways of said outer members; and a locking plug supported on the seats of said outer members, said filler element being normally supported on top of said plug and partly closing the open inner ends of said guideways, said filler element being upwardly displaceable with said plug when lifted to register the pocket of said element with the

open inner ends of said guideways, said plug being disengageable from said seats for lateral displacement into the guideway of one of said outer members clear of the filler element to permit removal of the latter in a downward direction, when said filler element is elevated to position the pocket thereof in registration with the open inner ends of the guideways of said outer members.

10 4. In car construction, the combination with body and truck bolsters having aligned center pin receiving openings; of a center pin insertable from beneath said truck bolster, said pin including a plurality of outer members headed at opposite ends; a filler element interposed between said outer members, said filler element holding the heads of the outer members in shouldered engagement with the bolsters; supporting shoulders on said outer members; and a locking ball supported on said shoulders, said ball supporting the filler element, said outer members being recessed to accommodate said ball for lateral displacement clear of said filler element to permit removal of the filler element in a downward direction, said shoulders being depressed with respect to said recesses.

15 5. In car construction, the combination with body and truck bolsters having aligned center pin receiving openings; of a center pin insertable from beneath the truck bolster, said pin including a plurality of outer members headed at opposite ends; a filler element interposed between said outer members, said filler element holding the heads of the outer members in shouldered engagement with the bolsters, said outer members having radial guide openings therein, and depressed supporting shoulders at the inner ends of said openings; and a locking ball supporting said filler element against downward displacement, said ball being supported on said shoulders of the guideways, said ball when lifted from said shoulders being laterally displaceable into the guideway of one of said outer members clear of said filler element to permit withdrawal of said filler element in a downward direction from between the outer members.

20 6. In car construction, the combination with body and truck bolsters having aligned center pin receiving openings; of a center pin insertable from beneath said truck bolster, said pin including a plurality of outer members headed at the top and bottom ends, a radial guideway in the lower head of each outer member, said guideway being inclined downwardly in inward direction; a depressed seat at the inner end of each guideway; a filler element interposed between said outer members, said filler element holding the heads of the outer members in shouldered engagement with the bolsters, said filler element having a portion thereof depending between the seats of the outer members, said depending portion having a pocket communicating with the guideways of said outer members, said pocket being normally in non registering relation with 25 said guideways and being registered with said guideways when the filler element is lifted to a predetermined extent from said normal position; and a locking ball supported on the seats of said outer members, said filler element in its normal position being supported on top of said ball, said filler element being upwardly displaceable with said ball when lifted, the guideway of any one of said outer members accommodating the ball for lateral displacement clear of the filler element, 30 said ball being laterally displaceable into any one

of said guideways when lifted out of said seats into alignment with said guideways, and when said filler element has been lifted to said predetermined extent.

7. In car construction, the combination with body and truck bolsters having aligned center pin receiving openings; of a center pin insertable from beneath said truck bolster, said pin including a plurality of outer members headed at opposite ends; a filler element interposed between said outer members, said filler element holding the heads of the outer members in shouldered engagement with the bolsters; supporting shoulders on said outer members; and a locking wedge block supported on said shoulders, said wedge block supporting the filler element, said outer members being recessed above said shoulders to accommodate said wedge block for lateral displacement clear of said filler element, said block, when lifted off of said shoulders into alignment with said recessed portions of said outer members being displaceable into the recess of one of said outer members to provide clearance for removal of said element in a downward direction.

8. In car construction, the combination with body and truck bolsters having aligned center pin receiving openings; of a center pin insertable from beneath the truck bolster, said pin including a plurality of outer members headed at opposite ends; a filler element interposed between said outer members, said filler element holding the heads of the outer members in shouldered engagement with the bolsters, said outer members having radial guide openings therein, and depressed supporting shoulders at the inner ends of said openings; and a locking wedge block supporting said filler element against downward displacement said wedge block being normally supported on said shoulders of the guide openings, said wedge block, when lifted off of said shoulders into alignment with said guide openings being laterally displaceable into the guide opening of any one of said outer members clear of said filler element to permit withdrawal of said filler element in a downward direction from between the outer members.

9. In car construction, the combination with body and truck bolsters having aligned center pin receiving openings; of a center pin insertable from beneath said truck bolster, said pin including a plurality of outer members headed at the top and bottom ends, a radial guideway in the lower head of each outer member, said guideway being inclined downwardly in inward direction; a depressed seat at the inner end of each guide-

way; a filler element interposed between said outer members, said filler element holding the heads of the outer members in shouldered engagement with the bolsters, said filler element having a portion thereof depending between the seats of the outer members, said depending portion having a pocket communicating with the guideways of said outer members and alignable therewith when the filler element is displaced upwardly to a predetermined extent; and a locking wedge block normally supported on the seats of said outer members with the filler element supported on top of said wedge block, said wedge block being laterally displaceable into the guideway of one of said outer members to clear the filler element for removal in a downward direction when said block is lifted off of said seats to upwardly displace said filler element to said predetermined extent.

10. In car construction, the combination with body and truck bolsters having aligned center pin receiving openings; of a center pin insertable from beneath said truck bolster, said pin including a plurality of outer members headed at opposite ends; a filler element having wings extending between said outer members, said filler element holding the heads of the outer members in shouldered engagement with the bolsters, said filler element having a depending portion extending between said outer members, and a pocket in said depending portion, said outer members having radial guideways disposed about said depending portion of said filler element, said guideways communicating with said pocket, each guideway having a depressed seat at the inner end thereof; and a locking plug within said pocket of the filler element, said plug normally resting on said seats and supporting said filler element against downward displacement, said plug being laterally displaceable from said pocket into one of said guideways to clear the filler element for removal in a downward direction when said plug is lifted out of said depressed seats.
